COMBINED CAN OPENER AND CUTLERY SHARPENER

Daniel E. McCue, Santa Barbara, Calif., assignor to Rival
Manufacturing Company, Kansas City, Mo., a corpo-
ration of Missouri

Filed Nov. 7, 1969, Ser. No. 19,985

Term of patent 14 years

Int. Cl. D8—02

U.S. Cl. D8—35

Fig. 1.

Fig. 2.

Fig. 3.

Fig. 4.

Fig. 5.

FIG. 1 is a front elevational view of a combined can opener and cutlery sharpener showing my new design; FIG. 2 is a top plan view thereof;

FIG. 3 is a side elevational view thereof;

FIG. 4 is a rear elevational view thereof; and

FIG. 5 is a side elevational view thereof, taken from the side opposite to that shown in FIG. 3.

I claim:

The ornamental design for a combined can opener and cutlery sharpener, as shown.
